E. E. Collin Inventor

By Kimmel & Crowell
Attorneys

1. A combination of articles of furniture, including a chair, a table or ironing board and a step ladder, which may be converted from one article to another, comprising a base unit having a lower side member 14, a horizontal connecting board 17 secured between the horizontal upper edges 18 of the opposite lower side members 14, and a pair of vertical side members 10 and 11 secured to the lower ends thereof, a pair of foot members 12 and 13 secured to the lower ends of the vertical side members 10 and 11, respectively, a horizontal board 22 secured to the upper ends of the extensions 15, and a back member 23 secured to the opposite edges of the horizontal board 22.

UNITED STATES PATENT OFFICE

2,512,827

ARTICLE OF FURNITURE

Einer Edward Collin, Grants Pass, Oreg.

Application April 26, 1945, Serial No. 590,345

2 Claims. (Cl. 155—41)

1

This invention relates to articles of furniture. An object of this invention is to provide a combination article of furniture which can be used as a chair, a table or ironing board and a step ladder.

Another object of this invention is to provide a device of this kind which can be easily and quickly converted from one article of furniture to another.

A further object of this invention is to provide a device of this kind which is simple in construction so that it can be made at relatively low cost and will withstand relatively hard usage.

A further object of this invention is to provide a device of this kind which will form an attractive article of furniture such as a chair or the like and which can be easily and quickly converted from a chair to either a step ladder or a narrow table or ironing board.

In the drawings:

Figure 1 is a detail front elevation of an article of furniture constructed according to an embodiment of this invention.

Figure 2 is a detail side elevation of the device formed as a chair.

Figure 3 is a sectional view taken on the line 3—3 of Figure 1.

Figure 4 is a detail side elevation of the device showing the position of the swingable back when used as a step ladder.

Figure 5 is a detail side elevation of the device when used as a table or ironing board.

Figure 6 is a fragmentary sectional view, taken on the line 6—6 of Figure 2.

Figure 7 is a fragmentary exploded view showing the pivotal connection and locking means for the two elements forming the article of furniture.

Figure 8 is a fragmentary plan view of the seat, showing the dove-tail joint between the horizontal and side members.

Referring to the drawings, the numerals 10 and 11 designate generally a pair of vertical side members forming the base unit, which have secured to the lower ends thereof foot members 12 and 13 respectively. The side members 10 and 11 are of like construction and each includes a lower relatively wide panel 14 having extending upwardly from the forward portion thereof an extension 15. The extension 15 is partly offset, as indicated at 16, from the forward edge of the lower member 14, and a horizontal connecting board 17 is secured between the horizontal upper edges 18 of the opposite lower side members 14. The rear edge of the extension 15 is provided with a substantially vertical lower edge portion 19, and an upwardly and rearwardly inclined edge

2

20 extends from the upper end of the vertical edge 19, and terminates at its lower portion in a curved socket forming edge 21. The upper ends of the extensions 15 are connected together by a horizontal connecting board 22, which may be dove-tailed or otherwise firmly secured to the upper ends of the extensions 15.

The horizontal board 22 comprises the forward portion of a seat. An elongated seat back, generally designated as 23, has secured to the opposite edges thereof, a pair of side forming members, generally designated as 24. The side forming members 24 include a relatively wide upper panel 25 and a relatively narrow extension 26 which extends from the rear portion of the panel 25. The extension 26 is formed with a vertical forward edge 27, which is adapted to abut against the vertical rear edge 28 of the lower side member 14. The lower edge of the upper panel 25 is horizontal and is adapted to overlie the horizontal upper edge 18 of the lower member 14.

A board 29 is secured between the lower end portions of the upper panel 25 and is adapted, when the device is in the form of a seat, to rest on the upper side of the horizontal board 17. The lower ends of the extensions 26 are connected together by a board 30 which is adapted to rest on the foot members 12 and 13 when the back member 23 is in back forming position. The forward edge of the upper side member 25 is vertical, as indicated at 31, and the forward edge of the side member 25 is also formed with a tapered wedge 32, which is adapted to engage against the inclined rear edge 20 of the upper side member 15 and to seat in the arcuate cutout 21.

The side members 25 are secured to the back member 23, and have secured to the outer sides thereof, at the upper ends, a pair of elongated bars 33. The bars 33, as shown in Figure 6, have extending therethrough, a headed pin 34, and the pin 34 is adapted to engage in a selected one of a pair of holes or sockets 35 and 36 which are formed in the upper side member 15.

In order to provide a means whereby the back member 23 may be locked in one of several of its positions, I have provided a pivoted latch member 37 which is pivotally mounted on a pivot member 38 carried by the side member 25. The latch member 37 is formed with a slot 39, within which a headed bolt or holding member 40 is adapted to engage, as shown in Figure 6.

As shown in Figure 2, the device, when disposed in a chair-forming position, has the bars 33 thereof substantially co-planar with the seat 55 which is formed by the board 22, and a second

board 41 which is secured between the upper ends of the side members 25. A second headed member or bolt 42 is carried by the side members 15, forwardly and upwardly from the headed members 40, and is adapted to be engaged by the latch member 37, as shown in Figure 5, when the back or table forming member 23 is in a substantially horizontal position.

The extensions 26 on the side members 24 form a pocket or chamber 43 at one end of the board 23, within which articles may be positioned when the device is used either as a chair or as a table or ironing board.

In the use and operation of this device when it is desired to use the article as a chair, the back member 23, which will be inclined to the vertical, as shown in Figure 2, will be disposed with the side members 24 abutting against the side members 10 and 11 of the base. At this time, the arms 33 will be substantially horizontal and the headed pins 34 will be engaged in the holes 36.

When it is desired to form the article into a step ladder, the latch members 37 are swung to a released position and the back 23 is then swung forwardly and downwardly so as to invert the back member. At this time the connecting board 17 will constitute the lower step and the seat forming board 22 will constitute the second step. The connecting board 29 will constitute the third step and the connecting member 30 will constitute the upper step.

When it is desired to use the article as a narrow table or ironing board, the pins 34 are removed from the sockets 36 and the pins are then extended through the arms 33 and engaged in the holes 35. The back member is raised upwardly before the bars 33 are locked so as to position the board 23 horizontally and with the edge 32 thereof resting on the top of the base member comprising the sides 10 and 11 and the connecting board 22. The latch members 37 are then engaged with the headed bolts 42. The board 23 will then be locked in its horizontal position.

What I claim is:

1. A combined seat, ladder and ironing board, comprising a base, opposite vertical side members on said base, an upright extension on each of

5 of said side members, a horizontal member between the upper ends of said extensions constituting a forward seat member, an elongated back member, a pair of panels secured to the opposite lengthwise edges of said back member, a connecting member between the upper ends of said panels and adapted to be disposed coplanar with said horizontal member to thereby form a complete seat, a forwardly extending arm carried by each of said panels, a pin carried by each of said arms at the free ends thereof, said side members formed with a pair of aligned openings therein, said pins engageable in said openings pivotally securing said side panels and back member to said side members whereby said back may be rocked about said pins to a raised ladder forming position from a lower seat forming position relative to said base, said side panels formed with a second pair of aligned openings therein below and rearwardly of said first openings, said pins when the back is rotated through 180° being engageable in said latter openings for supporting said back member in a horizontal position about said base with the front edges of said side panels abutting the upper edge of said side members thereby forming an ironing board, headed pins carried by said side members and a hook carried by each of said side panels engageable with said pins in the seat forming and ironing board forming position of said back member.

2. A combined seat, ladder and ironing board as set forth in claim 1, wherein said arms engage certain of said last mentioned pins for supporting said back member in ladder forming position.

EINER EDWARD COLLIN.
